DESIGN FOR A DIAMOND TOOL

Selden G. Warner, West Orange, N. J.

Application April 16, 1936, Serial No. 62,155

Term of patent 14 years

To all whom it may concern:

Be it known that I, Selden G. Warner, a citizen of the United States, residing at West Orange, in the county of Essex and State of New Jersey, have invented a new, original, and ornamental Design for Diamond Tools, of which the following is a specification, reference being had to the accompanying drawing, forming a part thereof:

Fig. 1 is a view in end elevation of a diamond tool showing my new design; and—

Fig. 2 is a view in side elevation of the diamond tool shown in Fig. 1.

I claim:

The ornamental design for a diamond tool, as shown.

SELDEN G. WARNER.
